UNITED STATES PATENT OFFICE.

GEORGE F. GILL, OF TYRONE, PENNSYLVANIA.

DESIGN FOR A GASOLENE-PUMP STAND.

53,965.

Specification for Design.

Patented Oct. 14, 1919.

Application filed May 2, 1919. Serial No. 294,332. Term of patent 14 years.

To all whom it may concern:

Be it known that I, GEORGE F. GILL, a citizen of the United States, residing at Tyrone, in the county of Blair and State of Pennsylvania, have invented a new, original, and ornamental Design for Gasolene-Pump Stands, as shown in the accompanying drawing, forming part of this specification.

In said drawing Figure 1 is a front view of the pump stand showing the peculiar ornamental configuration thereof. Fig. 2 is a top plan view. Fig. 3 is a transverse sectional view on line 3—3, Fig. 1.

The design as shown has an oblong vertically disposed base portion 1 approximately rectangular in section or four sided, and having paneled portions 9 and 10: on top of this base portion is a reducing portion 2, which merges from a substantially rectangular form at its lower end to a substantially

circular form at its upper end: from this reducing portion rises a cylindric column 3 slightly tapering from its lower to its upper end: on the upper end of this column is a branched member having radiating arms 4, from each of which, near its outer end, depends a globe-shaped lighting pendant 5; and above this branched member is a crown member 6, on top of which is a basket like member 7 supporting a globe-shaped light member 8.

I claim:

The ornamental design for a gasolene pump stand substantially as shown and described.

GEORGE F. GILL.
